UNITED STATES PATENT OFFICE.

GEORGE S. HOLLISTER, OF BOSTON, MASSACHUSETTS, ASSIGNOR TO GIBSON-HOLLISTER MANUFACTURING COMPANY, OF BOSTON, MASSACHUSETTS, A CORPORATION OF MASSACHUSETTS.

IGNITION DEVICE.

1,224,299.

Specification of Letters Patent. Patented May 1, 1917.

Application filed April 24, 1915. Serial No. 23,623.

To all whom it may concern:

Be it known that I, GEORGE S. HOLLISTER, a citizen of the United States, residing at Allston, Boston, in the county of Suffolk 5 and State of Massachusetts, have invented certain new and useful Improvements in Ignition Devices; and I do hereby declare the following to be a full, clear, and exact description of the invention, such as will 10 enable others skilled in the art to which it appertains to make and use the same.

The present invention relates to ignition devices for internal combustion motors, and more particularly to spark plugs employed 15 for igniting a charge of explosive gas.

It is desirable that the spark plugs employed with internal combustion motors shall be so constructed that they will operate indefinitely without short circuiting due 20 to carbon or lubricating oil bridging the spark gap, or to a leakage of oil which permits the flow of current from the high tension electrode to the outer metal shell of the plug.

25 An object of the present invention is to provide a spark plug having an improved construction and mode of operation in order to insure that the plug shall operate satisfactorily for an indefinite period without 30 liability of a short circuit by oil, carbon, or other foreign material.

With this object in view the several features of the invention consist in certain 35 novel features of construction, combinations and arrangements of parts hereinafter described and claimed, the advantages of which will be obvious to those skilled in the art from the following description.

40 In the accompanying drawings illustrating the preferred form of the invention; Figure 1 represents a longitudinal section in elevation of the improved spark plug; Fig. 2 is a bottom plan view of the plug shown in Fig. 1; Fig. 3 is a detail showing 45 an elevation of the lower portion of the plug; Fig. 4 is an elevation partly in section of a modified form of spark plug; and Fig. 5 is a bottom plan view of the plug shown in Fig. 4.

50 The spark plug shown in the illustrated embodiment of the invention consists of an outer metal shell 1 having an annular skirt 2 which is threadedly received in the cylinder of the internal combustion motor. The usual high tension electrode 5 is mounted in

a porcelain bushing 6 and is connected at its upper end with a terminal cap 7. The insulator bushing 6 is secured to the metal shell by a gland 8 threadedly engaging with the metal shell and yieldingly clamping the 60 bushing in the shell through copper asbestos washers 9. The porcelain bushing is provided with a counter-bored recess from which the lower end of the high tension electrode extends to form a sparking point. 65

It frequently happens that a considerable quantity of lubricating oil may collect upon the lower portion of the spark plug and electrodes and be consumed by the explosion of gas in the combustion chamber, leaving 70 carbon deposit upon the plug. Many attempts have been made to prevent the short circuiting of the plug by oil or carbon by either preventing the initial accumulation of the oil or carbon upon the plug, or by 75 so constructing the plug that this accumulation of carbon or oil will not prevent the passing of a spark. In the present invention the formation of a spark is insured by providing a plurality of electrodes which 80 successively receive the spark, thus causing a spark to be formed even though the spark gap between a single pair of electrodes may be temporarily bridged by carbon or oil. 85 To this end a low tension electrode is secured to the metal shell of the plug and an intermediate electrode is interposed in the path of the spark between the high and low tension electrodes to intercept the spark from the high tension electrode and deliver 90 it to the low tension electrode. A low tension electrode indicated at 11 is secured to the rim of the shell and an intermediate electrode 12 is secured to the insulating 95 bushing 6 with its lower end located between the sparking points formed upon the high tension electrode 5 and low tension electrode 11. The low tension electrode is shaped in such a manner that it may be firmly secured to the shell and at the same time will cause the draining of lubricating oil from the 100 sparking point. To this end the electrode 11 has its opposite ends secured to the rim of the metal shell and is provided with an elevated central portion to act as a sparking point, and depressed portions upon each side to cause the draining of oil from the sparking point. This form of electrode is conveniently made by bending the electrode into 105 the shape of a W, and securing the opposite

110

ends of the electrode to the shell with the peak of the **W** arranged to receive the spark. The intermediate electrode is provided with an upwardly bent portion 14 which extends in the direction of the spark gap to provide for the draining of oil from the two sparking points of the electrode, as shown clearly in Fig. 1.

It is desirable to prevent the leakage of oil between the high tension electrode and the insulating bushing and consequent short circuiting of the plug and to further provide a tight joint between the electrode and bushing. To this end each of the electrodes 5 and 12 is provided with an insulating shell 15 of mica which is received closely in the recess formed in the insulating bushing, and a seal 16 of permanently flexible cement is received in the counterbored portion of the recess surrounding the electrode, as shown clearly in Fig. 1. This cement prevents the passage of gas from the combustion chamber between the electrode and insulating bushing and due to its permanent flexibility permits the relative movement of the electrode and bushing owing to different co-efficients of expansion without destroying the seal.

In the modified form of spark plug shown in Figs. 4 and 5 the insulating bushing is provided with a central recess 17 and a high tension electrode 18 extending into the recess. The intermediate electrode is formed by a metal ring 20 secured to the lower face

of the bushing by pins 21 and arranged to receive the spark from the high tension electrode. The spark is received from the ring 20 by a plurality of electrodes 22 secured in the rim of the metal shell and having upwardly bent portions 23 to form the sparking points, as shown clearly in Fig. 4. With this construction, the spark is formed between the high tension electrode and the metal ring and between the metal ring and the low tension electrode secured to the metal shell.

While it is preferred to employ the specific construction and arrangement of parts shown and described, it will be understood that this construction and arrangement is not essential except so far as specified in the claim, and may be changed or modified without departing from the broader features of the invention.

The invention having been described, what is claimed is:—

A spark plug comprising a metal shell, an insulating bushing secured in the shell, a high tension electrode supported in the bushing, an annular ring secured to the bushing and surrounding the lower portion of the high tension electrode, and a plurality of low tension electrodes secured to the shell and having upwardly bent portions arranged to receive the spark from the annular ring.

GEORGE S. HOILLISTER.
